HOSE STRAP

Theodore Ziaylek, Jr., P.O. Box 292,
Yardley, Pa. 19068

Filed Sept. 12, 1969, Ser. No. 19,124

Term of patent 14 years

Int. Cl. D8—03

U.S. Cl. D8—230

Fig. 1.

Fig. 2.

Fig. 3.

FIG. 1 is a front perspective view of a hose strap embodying my new design, part being broken away;

FIG. 2 is a rear elevational view, partly broken away; and

FIG. 3 is a side elevational view, partly broken away.

The strap is shown broken away in part in FIGS. 1, 2 and 3 to indicate indeterminate length.

I claim:

The ornamental design for a hose strap, as shown and described.
